UNITED STATES PATENT OFFICE.

EDWARD G. WOODS, OF MARCELLUS, NEW YORK.

AUTOMATIC STOP-MOTION FOR FEEDING MECHANISMS OF CARDING-ENGINES.

SPECIFICATION forming part of Letters Patent No. 329,425, dated October 27, 1885.

Application filed June 2, 1885. Serial No. 167,379. (No model.)

To all whom it may concern:

Be it known that I, EDWARD G. WOODS, of Marcellus, in the county of Onondaga, in the State of New York, have invented new and useful Improvements in Automatic Stop-Motions for Feeding Mechanisms of Carding-Engines, of which the following, taken in connection with the accompanying drawings, is a full, clear, and exact description.

10 This invention relates to automatic stop-motions applied to the well-known "Apperley's Feeders," connected to the species of wool-carding machines designated "condensers," and has more particularly reference to 15 the apparatus shown in the Patent No. 62,917, granted to Ainsworth and Wright, March 19, 1867, of which this invention is a specific improvement.

20 My improvements consist in connecting the tripper to the reciprocating feed-carrier and arranging at opposite sides of the condenser-frame levers adapted to be encountered and actuated by the tripper when allowed to assume its normal position by the breakage of 25 the roving, said levers communicating with the catch which holds the shifter for throwing in and out of gear the actuating mechanism of the condenser, and when actuated by the tripper, as aforesaid, the levers release the catch, 30 and thereby allow the shifter to throw the actuating mechanism of the condenser in gear, said combination and arrangement of devices causing a stoppage of the machine automatically with the breakage of the roving during 35 the travel of the feed-carrier toward either side of the feed-bed, whereas in the hereinbefore-referred-to prior devices the feed-carrier was allowed to travel twice the width of the feed-table before tripping the catch which 40 holds the actuating mechanism of the machine in gear.

45 My invention also consists in an improved construction and combination of the component parts of the automatic stop-motion, all as hereinafter more fully described, and specifically set forth in the claims.

50 In the annexed drawings, Figure I is a perspective view of that part of the finisher or condenser to which the Apperley's feeder is applied. Fig. II is an enlarged front view of the said feeder and my invention connected

therewith. Fig. III is a plan view of the same, taken below the line $x x$ in Fig. II, and Fig. IV is a vertical transverse section on line $y y$, Fig. II.

55

Similar letters of reference indicate corresponding parts.

A represents the so-called "finisher" or "condenser" employed in connection with wool-carding machines, similar to that shown 60 in the patent to Ainsworth and Wright, hereinbefore referred to. B denotes the reciprocating feed-carrier of the well-known Apperley's feeder, for which Apperley and Clissold have obtained Letters Patent of the United 65 States No. 18,888, December 22, 1857, said feed-carrier B being mounted on the front end of the frame of the finisher A in the usual manner. The carrier B slides on a guide-rod, 70 r , extended across the feed-table of the finisher A, and is automatically carried alternately in opposite directions across the said feed-table by an endless belt, D, running on revolving pulleys C C, which are pivoted on opposite ends of the supporting-frame of the feed, and receive motion from one of the revolving shafts of the condenser A by gears, pulleys, and belt connections in the usual and well-known manner, not necessary to be here illustrated.

A spur, f, projecting from the belt D and into 75 a vertical slot, h, in the carrier B, carries the latter along with the travel of the belt. A pivoted catch, g, at each end of the feed-frame holds the roving down upon the feed-table, while the carrier B travels across to the opposite side of the said table and deposits upon 80 the table the succeeding lap or layer of roving. On a horizontal extension of the base of the carrier B, and reaching under the belt D, are pivoted two rollers, n n, between which 85 the roving passes. The carrier B carries a tripping-arm, e, which is pivoted on a bracket, i, attached to the carrier B. One end of the tripping-arm reaches under the aforesaid carrier and toward the rollers n n, so as to lie in 90 the passage of the roving and be traversed by the same, the pressure of the roving serving to depress said end of the arm e. The opposite end of the tripping-arm e is weighted, so as to cause it to automatically tilt the arm so 95 soon as it is released from the aforesaid pressure of the roving; hence said action of the arm

e is produced in case the roving becomes disrupted. At opposite sides of the frame of the condenser *A* are pivoted two levers, *c c'*, each of which has one of its arms so arranged as to be encountered by the approaching tripping-arm *e* when released from the pressure of the roving and tilted into its normal position by the weighted end of said arm, and to allow the tripping-arm to pass freely over said lever-arms when the former is tilted into its abnormal position by the pressure of the roving, as hereinbefore described. By means of springs *u u* the levers *c c'* are held yieldingly in their described position. The lever *c* has connected to it a catch, *b*, which engages the shifter by which the actuating mechanism of the machine is thrown in and out of gear. Said shifter may in some machines consist of a lever for moving a clutch, or other well-known and equivalent devices for connecting and disconnecting actuating mechanisms. In this case said shifter consists of the lever *S*, arranged to throw the driving-belt of the card-cylinder from the driving-pulley onto the loose pulley, the catch *b* aforesaid being provided with a notch, *o*, by which it interlocks with the lever *S*, and when so interlocked it holds the lever in position for maintaining the belt on the driving-pulley; otherwise the lever *S* is held normally in position for holding the belt on the loose pulley or for throwing the actuating mechanism of the machine out of gear by a suitable spring, *a*, drawing or pressing said lever in said position. To another arm of the lever *c'* is connected a rod or push-bar, *d*, by which it engages a secondary arm on the lever *c*, and when actuated by the collision of the tripping-arm *e* the lever *c'* transmits motion to the lever *c* by the aforesaid rod *d*, so as to throw the catch *b* out of engagement with the belt-shifting lever *S*, and thus allow the spring *a* to throw said lever in position for carrying the driving-belt onto the loose pulley. The same effect is produced by the collision of the tripping-lever *e* with the lever *c*.

From the foregoing description it will be observed that the tripper *e* is held in abnormal position and allowed to travel freely back and forth with the feed-carrier *B* so long as the roving passes over it; but so soon as the roving is severed and its passage to the feed ceases, the tripper falls into its normal position and is caused to collide with one of the levers *c c'*, either of which throws the catch *b* out of engagement with the shifting-lever *S*, which is then immediately thrown by the spring *a* into position for carrying the driving-belt onto the loose pulley, and consequently the motion of the machine is stopped automatically with the severing of the roving passing to the machine.

The stop-motions heretofore employed on wool-carding machines were only connected with the actuating mechanism of the feed of the machine, and did not affect the operation of the card-cylinder; hence in case of the breakage of the roving or sliver it was neces-

sary to immediately reunite the same, and if this was neglected the card-cylinder would run empty and produce an almost irreparable breakage of the condensed roving on the spools. By my invention the motion of the card-cylinder is stopped automatically with the breakage of the roving; hence the aforesaid injurious results are entirely obviated. By placing the levers *c c'* at opposite ends of the path of the tripper *e*, and providing said levers with means for transmitting motion to the catch *b*, the stoppage of the machine is effected during the travel of the feed-carrier toward either side of the feed-table, and consequently more quickly than by the prior devices.

Having described my invention, what I claim as new, and desire to secure by Letters Patent, is—

1. In combination with the actuating mechanism of the condenser, and the reciprocating feed-carrier, and mechanism for automatically moving said feed-carrier, as described, a shifter held normally in position for holding said actuating mechanism out of gear, a catch for holding the shifter in its abnormal position, a lever pivoted at one side of the condenser-frame and connected with the aforesaid catch, a lever pivoted at the opposite side of the aforesaid frame, a rod extending from lever to lever, and a tripping-arm carried on the feed-carrier and normally in position to actuate the aforesaid levers, and arranged to be traversed by the roving passing through the feed, and thereby held in abnormal position, substantially as described and shown.

2. The combination, with the driving-belt, of the condenser *A* and the reciprocating feed-carrier *B*, and mechanism for automatically moving said feed-carrier, as described, of the belt-shifter *S*, the spring *a*, for throwing the belt-shifter to carry the belt onto the loose pulley, the catch *b*, for holding the belt-shifter to maintain the belt on the driving-pulley, the lever *c*, connected to said catch and arranged at one end of the path of the feed-carrier *B*, the lever *c'* at the opposite end of the path, the rod *d*, for transmitting motion from the lever *c'* to the lever *c*, and the pivoted arm *e*, carried on the feed-carrier, and having one end weighted to depress it into position for colliding with the levers *c c'*, and the opposite end in the feed-passage to receive the pressure of the roving passing through said passage, and thereby become tilted to clear the aforesaid levers, substantially in the manner specified and shown.

3. In combination with the frame of the condenser, driving-belt of the card-cylinder, reciprocating feed-carrier *B*, and mechanism for moving said feed-carrier, as described, a spring-actuated belt-shifter arranged to hold said driving-belt on the loose pulley, a catch for holding the belt-shifter on the driving-pulley, a lever pivoted on the frame and connected with the catch, and a tripper carried

on the feed carrier and normally in position to actuate the aforesaid lever, and arranged to be traversed by the roving, and thereby held in abnormal position, the whole combined and arranged to stop the motion of the card-cylinder automatically with the breakage of the roving, substantially as set forth.

5 In testimony whereof I have hereunto signed

my name and affixed my seal, in the presence of two attesting witnesses, at Syracuse, in the 10 county of Onondaga, in the State of New York, this 18th day of April, 1885.

EDWARD G. WOODS. [L. S.]
